UNITED STATES PATENT OFFICE.

ANDREW BENSON, OF JANEVILLE, WISCONSIN, AND LEWIS E. CURTIS, OF KENILWORTH, ILLINOIS, ASSIGNEES TO PROGRESSIVE STEEL COMPANY, OF DETROIT, MICHIGAN, A CORPORATION OF MICHIGAN.

PROCESS OF FORMING EXPANDED METAL.

1,292,685.

Specification of Letters Patent. Patented Jan. 25, 1913.

Application filed October 6, 1912. Serial No. 256,941.

To all whom it may concern:

Be it known that we, ANDREW BENSON and LEWIS E. CURTIS, citizens of the United States, and residing at Janesville, county of Rock, and State of Wisconsin, and Kenilworth, county of Cook, and State of Illinois, respectively, have invented a new and Improved Process of Forming Expanded Metal, of which the following is a specification.

This invention relates to the manufacture of metal lath of that type or class in which continuous strands extending diagonally from one edge of the sheet to the other, cross each other, the strands being integrally united at their intersections to form what is often known commercially as "diamond mesh metal lath", and the present process is a modification of the process set forth in our prior application No. 220,384, filed April 3rd, 1912, and consists in positioning a previously slitted sheet at an oblique angle to the parallel paths of movement of the meshes as they are formed along the opposite edges of the sheet, so that the sides of the meshes as they are formed along each edge of the sheet will move along a plane in parallel paths and preserve their original distances from each other.

This invention consists in a process of producing reticulated metal from a sheet formed with parallel lines of short slits, the spaces between the slits of one line being opposite the slits of the adjacent lines, and consists in so positioning the slitted sheet at an oblique angle to the parallel paths of the expanded meshes as they are formed along both side edges of the sheet that the distance between two planes contacting with the ends of said sheet and positioned parallel to said paths is substantially equal to the length of the desired expanded material, and then expanding the slitted sheet by bending out the strands which form the meshes so as to carry out these strands at the opposite edges of the sheet in opposite directions from said opposite side edges in parallel planes while still permitting the strands to remain parallel to the slitted sheet.

It also consists in bending long sheets of properly slitted sheet metal intermediate their ends transversely to the lines of the slits and then simultaneously expanding the

several sections of the sheet by the present process.

It further consists in securing the slitted sheet between a pair of relatively movable holding members or platens which will prevent more than one diagonal strand being started away from any section of the sheet.

In the accompanying drawings, Figure 1 is a plan and Fig. 2 an edge view of the slitted sheet. Fig. 3 is an edge view of the slitted sheet after being bent. Fig. 4 is a perspective view of this sheet after the first meshes are formed. Fig. 5 is a similar view after a series of rows of meshes are started. Fig. 6 is a view of this sheet just before expansion is completed. Fig. 7 is a section on the line 7-7 of Fig. 6. Fig. 8 is a perspective view of a slitted sheet bent to form four sections, meshes being formed at the corners of each section. Fig. 9 is a perspective view of one end of an expander bar. Fig. 10 is a central, vertical section of a machine for carrying out the present process, with the platens omitted. Figs. 11 and 12 are sections on the line 11-11 and 12-12 of Fig. 10 respectively. Fig. 13 is a front elevation of the machine. Figs. 14 to 17 inclusive are diagrams showing the action of the expanding bars and of the platens.

Similar reference characters refer to like parts throughout the several views.

In the manufacture of the expanded metal of "diamond mesh" type shown in the drawings wherein the strands are moved out from the plane of the slitted sheet to produce the meshes, provision has usually been made for the shortening of the sheet as the expansion proceeds. This is commonly done by so constructing the expanders that the parts that engage the strands along the edge of the sheet may move toward each other as the expansion proceeds.

In the present process, the devices that engage these edges of the sheet may be rigid as the parts of the sheet retain their relative distances from the plane parallel to the paths of movement of the engaging devices from the time the slitted sheet is finally positioned until the expansion is completed. These paths of movement are at oblique angles to the sheet being expanded, and the sheet is so positioned that the projected length of the slitted sheet on a plane per-

perpendicular to the paths of movement of the meshes will substantially equal the desired length of the expanded material. The metal of the meshes moves away from the sheet in parallel lines and the relative positions of the particles do not change from the instant that the meshes are formed.

Each mesh is formed by four sections of strands and two of these strands 1 and 2 continue parallel to the slitted sheet as it was positioned previous to expanding.

The sheet 1 of metal is formed with short slits 2 in parallel lines, the metal between the slits of one line being opposite the slits 3 of the two adjacent lines. While a single flat strand may be so positioned that its projection in a plane perpendicular to the paths of the meshes as the sheet is being expanded will be substantially equal to the intended length of the expanded material, we prefer to bend the sheet one or more times intermediate its ends transversely to the lines of the slits, and treat each section of the sheet as a separate sheet, that is, begin the expansion of corresponding corners of such section, no matter how many are formed. The angles between the sections of the sheet are such that the distance between the outer ends of any two adjacent sections substantially equals the intended length of the expanded material A to be formed from these two sections.

Where the sheet is in two sections, we prefer to begin operations with the strands 3 and 4 at the outer corners and with the strands 5 and 6 at two diagonally opposite inner corners, and bend these strands away from the sections to carry the strands 7 and 8 away from the planes of these sections but permitting them to remain parallel thereto. At the continuation of the movement, the additional strands 9 and 10, and 11 and 12, and two more sections of each of the strands 3, 4, 5 and 6 are bent out to move out parts of the strands 11, 12 and 13.

It will be noticed that the small rectangles 17 of metal which constitute the ends of the diagonal strands remain substantially in the planes of the ends 18 of the original sheet 1, and that the strands 7 and 14 and 9, 15 and 16 and other parallel thereto remain parallel to the sections from which they are produced. The metal constituting the side edges of the sheet of which edges the strands 7 and 8 form a part, that is, the metal outside of the first lines of slits, will be engaged by sets of hooks which are rigidly secured to the expanding bars.

This sheet could not be expanded by the machine shown in Figs. 1 to 17 without side edges 11 and 12 being engaged by a shaft 23 which may be driven by means of a pulley 24 supported by an arm of a pulley 25. Such a shaft 23 is shown in Fig. 17 carrying a connecting rod 27 which in

attaches to a pin 28 on the adjacent vertically movable rack bar 29. These rack bars engage the gears 30 and 31 which revolve on the pins 22 and are connected to the gears 32 and 34 which mesh with the horizontal 20 movable rack bars 35 and 36. Vertically slidable rack bars 37 mesh with the gears 30 and the expander bar 38 connected to the rack bars 37 moves down as the expander bar 39 connected to the rack bars 29, 35 moves up.

Secured to the rack bars 35 and in addition therewith is an upper platen 41. A marker 42 for the lower platen 43 is secured to the rack bars 36 and has bearings for the shafts 44 and 46 which support the arms 44 and 45. A link 48 connects a handle 50 to the small crank 51. A handle 50 on the shaft 45 enables the operator to swing these arms up and down and thus raise and lower the 26 lower platen 43.

A sheet 1 of slitted material is placed between the platens as shown in Fig. 13 and the arms are swung up to cause the platens to bend the sheet transversely. The clutch 26 is then thrown in which causes the rack bar 29 and the expander bar 39 to rise and the rack bars 37 and the expander bar 38 to descend. At the same time the rack bars 37 move back or toward the left in Fig. 10 and the rack bars 35 move forward.

In Figs. 14 to 17, the operation of the device is indicated diagrammatically. The sheet 1 on the lower platen is indicated in Fig. 14 and the bent sheet and elevated lower platen in Fig. 15. When the expander bar 39 starts to move up its teeth 53 engage the outer adjacent corners of the sheet particularly the strands 3-7 of Fig. 2. At the same time the teeth of the bar 38 101 as it descends engage the strand 5-8-5 of the diagonally opposite corners of the two sections.

If the edges of the platens were straight up and down, there would be no continuous support for the unexpanded portions of the sheet. We therefore incline the front edges 54 of the upper platen and the rear edges 55 of the lower platen, as shown in Figs. 14 to 17. The other faces are also inclined but 115 only to permit the expander bars to move freely. When the parts are as in Fig. 15, the teeth on the expander bars are engaging to produce the effect shown in Fig. 2. The platens now move horizontally while the 120 expander bars move vertically so that the teeth in the expander bars will consecutively engage in each of the edge rows of slits and draw two parallel rows of metal at the edges of the sheet, which edges are shown 125 at the top and bottom of Fig. 3. But the continuous movement of the platens release the end lines of metal as that the expansion of these rows follow in proper order.

Fig. 14 perfectly all the angles of the sheet 130

have been expanded, the platens will have released the sheet, after which an additional movement of the parts will stretch the sheet to the desired size as indicated in Fig. 17. The handle 50 is now thrown back to lower the lower platen and the continued turning of the cranks will cause the expander bars to reverse their movements and release the expanded sheet which may be removed from the machine.

In each case the corners of each section at which the expansion is begun are respectively farthest from the transverse line toward which the meshes are moved. That is, expander bars engage the nearest corners.

It will be evident that other and further duplications and modification of details and proportions may be made by those skilled in the art, and the process which forms the subject matter of this invention may still be employed. As indicated in Fig. 8, while the sheet 1 may be bent up into four sections the expansion will be the same as above described.

25 We claim:

1. The process of expanding sheet metal formed with parallel rows of short slits, which consists in subjecting the material of the sheet to tensions transverse to the planes of the slotted sheet, the expansion commencing at diagonally opposite corners of the sheet and progressing along lines diagonal to the lines of slits, and the expanded material being moved in opposite directions away from the original sheet in constant planes.

2. The process of producing expanded metal which consists in providing a sheet of metal with parallel lines of short slits, curing the sheet with its edges parallel to the plane paths of a pair of expanders provided with a series of engaging means, the sheet being diagonal to said paths and substantially perpendicular to such planes, and then moving the expanders in opposite directions across the edges of the sheet so that the sections of the edges of the sheet outside of the slits along the edges of the sheet next to the paths of the expanders will be engaged one after another until all are engaged, and then continuing the movement until the sheet is entirely expanded.

3. The process of producing expanded metal which consists in providing a sheet of metal with parallel lines of short slits, bending the sheet intermediate its ends transversely to the lines of slits into sections, securing the sheet with the edges of the sections parallel to the path planes of expanders provided with engaging devices, each section being diagonal to such paths and substantially perpendicular to the planes, and then moving the expanders in opposite directions across the edges of the sections so that said engaging devices on the expand-

ers will engage in one after another of the slits along the edges of the sections adjacent the path of the expander until all are engaged, and then continuing the movement until the sheet is entirely expanded, said sheet being gripped between engaging surfaces which recede in opposite directions to gradually release the metal as the expansion proceeds.

4. The process of producing expanded metal which consists in providing a sheet of metal with parallel lines of short slits, bending the sheet intermediate its ends transversely to the lines of slits into sections, securing the sheet with the edges of the sections parallel to the path planes of expanders provided with engaging devices, each section being diagonal to such paths and substantially perpendicular to the planes, and then moving the expanders in opposite directions across the edges of the sections so that said engaging devices on the expanders will engage in one after another of the slits along the edges of the sections adjacent the path of the expander until all are engaged, and then continuing the movement until the sheet is entirely expanded, said sheet being gripped between engaging surfaces which recede in opposite directions to gradually release the metal as the expansion proceeds, the engagement of the slits being begun at diagonally opposite corners of the sections which are farthest from the lines toward which the expanders move.

5. The process of forming metal lath consisting in providing a sheet of metal with parallel lines of short slits, and then moving the strands thus formed outward from the sheet, beginning at diagonally opposite corners, in opposite directions from the sheet.

3. The process of forming metal lath consisting in providing a sheet of metal with parallel lines of short slits, bending the sheet transversely to the lines of slits into sections, and then moving the strands outwardly from the sheet beginning simultaneously at diagonally opposite corners of each section.

7. The process of forming metal lath consisting in providing a sheet of metal with parallel lines of short slits, the spaces between the slits of each line being opposite the slits of the two adjacent lines, the lines of slits being separated by continuous strands, then moving the strands thus formed outward from the sheet, beginning at diagonally opposite corners in such path planes that the projection of the sheet on a plane perpendicular to said path planes will have substantially the same width as the intended expanded sheet.

8. The process of forming metal lath consisting in providing a sheet of metal with parallel lines of short slits, the lines of slits

being separated by continuous strands, then moving the strands thus formed outward from the sheet, beginning at diagonally opposite corners, in parallel path planes that the projection of the sheet on a plane perpendicular to said path planes will have substantially the same width as the intended expanded sheet, said path being at an oblique angle to said slitted sheet.

30 9. A process for producing expanding metal which consists in forming a sheet with parallel lines of short slits, then moving the metal at the outside of an end slit of each of the outside lines of slits away from the plane of the sheet the width of one mesh at an acute angle to the sheet, then moving

these meshes and the metal at the outside of the next slits of the same lines away from the plane of the sheet the width of a mesh at the same acute angle to the sheet, and 20 then continuing the same operation, the metal adjacent the next slits of the first lines being engaged without disengaging the previously engaged portions after the forming of each new line of meshes until all the slits 25 have been opened to produce meshes, after which the metal of all the outer meshes of each edge is moved onward as a unit until the entire sheet is expanded.
